UNITED STATES PATENT OFFICE.

GEORGE KINGSTON, OF FORT MYERS, FLORIDA, ASSIGNOR TO KINGSTON PRODUCTS CORP., OF KOKOMO, INDIANA, A CORPORATION OF INDIANA.

GAS REGENERATOR.

Application filed August 22, 1925. Serial No. 51,727.

This invention relates to a gas regenerator and particularly to a device which is adapted to effectively heat a gaseous fuel mixture prior to its introduction into the combustion 5 chambers of an engine.

It is an important object of this invention to provide a device of the kind described wherein the heating of the in-flowing gas is instantaneous upon starting of the engine.

10 It is a further object of this invention to provide a gas regenerator wherein a circulation of the heating medium is due to the differential pressures existing within the exhaust and intake systems of the engine.

15 It is another important object of this invention to provide a device of the class described wherein a flash heating effect is brought about.

20 It is another important object of this invention to provide a device of the class described which effects instantaneous heating of the in-flowing fuel mixture to cause immediate operation of the engine in an efficient and economical manner.

25 It is finally an important object of this invention to provide an instantaneous gas regenerating apparatus of simple construction which permits of operation with low grade fuels and which facilitates proper operation 30 of the engine without excessive use of a choke valve or other air limiting means.

Other and further important objects of this invention will be apparent from the specification and the accompanying drawings.

35 The invention (in a preferred form) is shown on the drawings and hereinafter more fully described.

On the drawings:

40 Figure 1 illustrates a central longitudinal section taken thru an apparatus embodying the present invention.

Figure 2 is an enlarged fragmentary detail section of the exhaust gas inlet casing.

As shown on the drawings:

45 The reference numeral 1 indicates an intake manifold for an internal combustion engine which may be of any conventional construction and which is provided with a depending conduit 2 which is flanged as at 3 for attachment to a carburetor or other vaporizing device. The upper wall of said intake manifold which is provided with an annular seat 4, affords a support for the lower portion 50 of a usual exhaust manifold 6. The exhaust manifold is open at said lower portion 55

5 and projecting thru said opening therein is a grooved boss 7 which opens into the exhaust manifold. The upper wall of the intake manifold is provided with a threaded opening inside said grooved boss and the lower 60 end of said threaded opening is provided with a flange or shoulder 8 which affords a support for an integral flange 9 formed on the upper end of a conduit 10 which is of relatively thin material and which extends downwardly thru the conduit 2 to a region of sub-atmospheric pressure within said conduit or in certain instances within the carburetor itself. The conduit 10 may be secured in the position shown by the lower threaded end 11 65 of an apertured casing 12 which projects into the interior of the exhaust manifold to a desired region of relatively high temperature. It will be understood that if desired, the conduit 10 may be secured directly to the casing 70 12 in any suitable manner, the flange 9 in such cases being omitted.

In operation, the device of this invention acts as a flash or instantaneous heater which effectively completes the vaporization of the 80 in-flowing fuel mixture. Heated exhaust gases from the interior of the manifold 6 instantaneously flow through the apertures in the casing 12 as indicated by the arrows, flowing thence downwardly due to the existing 85 differential pressures and outwardly thru the lower end of the conduit 10 into the fuel mixture stream in the conduit 2. This flow of heated gases thru the conduit 10 of course serves to heat said conduit to a high temperature and brings about an instantaneous and 90 complete vaporization of the fuel mixture in the conduit 2.

It will be evident that by the use of this invention it is possible to bring the motor to an efficient operating condition in a minimum 95 time without the use of a choke valve or other air limiting means and consequently an efficient and economical engine operation is assured and at the same time excessive crank-case dilution is obviated.

100 It will be apparent that the device of this invention is simple, inexpensive and easy to install and it will be further evident to those skilled in the particular art to which this invention pertains, that complete and efficient vaporization of even low grade fuel mixtures 105 is assured thereby.

Due to the fact that the conduit 10 extends downwardly for a considerable distance 110

the in-flowing fuel mixture is heated at a relatively early point in its travel and consequently distribution thereof thru the manifold is greatly enhanced.

5 I am aware that numerous details of construction may be varied thru a wide range without departing from the principles of this invention and I therefore do not purpose limiting the patent granted hereon otherwise than necessitated by the prior art.

10 I claim as my invention:

1. In an internal combustion engine the combination with the exhaust and intake manifolds of an open ended conduit supported in the intake manifold and communicating with the exhaust manifold and an apertured casing in the exhaust manifold for supporting said conduit in position and limiting the flow of exhaust gases therethrough.

15 2. In an internal combustion engine the combination with the exhaust and intake manifolds of an open ended conduit of relatively thin material supported in the intake

25 manifold and communicating with the exhaust manifold and an apertured casing in the exhaust manifold at a point of relatively high temperature for holding said conduit in position and limiting the flow of exhaust gases therethrough.

30 3. The combination with the exhaust and intake manifolds of an internal combustion engine of a flanged threaded opening in the intake manifold, an aperture in the wall of the exhaust manifold adjacent said threaded opening, a conduit extending into the intake manifold having a flange at one end thereof seated on the flange at said opening and an apertured threaded casing engaging said threaded opening and said flange on the conduit for securing the conduit in position and permitting a limited flow of heated exhaust gases thru said conduit.

35 40 In testimony whereof I have hereunto subscribed my name.

GEORGE KINGSTON.
